UNITED STATES PATENT OFFICE.

ALLEN H. BLAKE, OF ELOISE, MICHIGAN.

DESIGN FOR A TRACTOR.

54,371.

Specification for Design.

Patented Feb. 10, 1920.

Application filed October 14, 1918. Serial No. 258,122. Term of patent 14 years.

To all whom it may concern:

Be it known that I, ALLEN H. BLAKE, a citizen of the United States, residing at Eloise, in the county of Wayne and State of Michigan, have invented a certain new, original, and ornamental Design for a Tractor, of which the following is a specification, reference being had to the accompanying drawing, forming a part thereof.

The drawing is a perspective view of a tractor body and running gear showing my improved design.

I claim:

The original and ornamental design of a tractor as shown.

ALLEN H. BLAKE.
